VISE JAW FACE PLATE

Arthur M. Maroth, Wilton, Conn., assignor of one-third to Kay Christensen, Norwalk, Conn., and one-third to William C. McTarnahan, New York, N. Y.; Grace Kaber McTarnahan, Walter N. Maguire and Bankers Trust Company, executors of said William C. McTarnahan, deceased

Application July 9, 1951, Serial No. 235,710

1 Claim. (Cl. 81—38)

1

The present invention relates to face plates for vise jaws, and is particularly related to face plates which are removable from the associated vise jaws.

An object of the present invention is to provide removable face plates for vise jaws which are constructed and arranged to be immovably attached to the related vise jaws so that the work may be securely and fixedly gripped by the face plates.

Another object is to provide face plates of the character described which are constructed to permit refinishing of the active faces thereof so that a smooth surface may always be provided for gripping contact with the work.

Still another object is to provide face plates for vise jaws which are sturdy and simple in construction, and adapted to mounting upon vise jaws of different configuration without requiring any modification of the vise jaws.

The above, and other objects, features and advantages of the present invention, will be manifest in the following detailed description of a preferred illustrative embodiment, the description being read in connection with the accompanying drawing, forming a part hereof and wherein:

Fig. 1 is a perspective view of a face plate embodying the present invention;

Fig. 2 is a rear elevational view of the face plate appearing in Fig. 1;

Fig. 3 is a bottom plan view of the face plate of Figs. 1 and 2;

Fig. 4 is a vertical sectional view taken along the line 4—4 of Fig. 2; and

Fig. 5 is a side elevational view showing two face plates embodying the present invention installed in operative position on a pair of vise jaws.

Referring to the drawing in detail, a face plate embodying the present invention is there shown and generally indicated by the reference numeral 10. The face plate 10 is preferably formed by casting, either in a sand mold or under pressure in a die, and may be made of any suitably soft material of sufficient strength, such as, for example, phosphor-bronze.

The face plate 10 includes a face member or portion 12 of substantially rectangular configuration having a depth and length sufficient to extend across and cover the gripping face of the vise jaw to which the plate is to be secured. The face portion 12 preferably has a thickness of at least three-sixteenths of an inch so that the gripping or front surface 14 thereof may be repeat-

2

edly ground or otherwise refinished to always present a smooth and unscarred surface for gripping contact with the work, without reducing the thickness of the face portion 12 beyond that point where the latter has sufficient strength to withstand the stresses attending the securing of the face plate to the related vise jaw in accordance with the present invention.

Ears 16 and 18 extend rearwardly from the opposite ends of the face portion 12 to overlie the opposite ends of the vise jaw when the face portion 12 is abutted against the gripping face of the vise jaw. The ears 16 and 18 are integral with the face portion 12 and are of substantial thickness to resist spreading apart when the face plate 10 is secured to the vise jaw in the manner hereinafter recited.

A flange 20 extends rearwardly along the top edge of the face portion 12 and is integral, at 20 its opposite ends, with the ears 16 and 18 to further insure against spreading apart of the latter. The unitary construction of the front or face portion 12, the ears 16 and 18 and the flange 20, provides a rigid assembly which permits the use 25 of a relatively soft metal in forming the face plate so that the work gripped thereby will not be indented or otherwise marred.

In attaching the face plate 10 to a vise jaw, the face portion 12 is arranged against the gripping face of the jaw, with the ears 16 and 18 overlying the opposite end portions of the jaw and with the flange 20 extending over the top surface of the jaw. In order to hold the face plate 10 in the above position, a tapped hole 22 (Fig. 4) is formed through one of the ears, in the illustrated case the ear 16, and threadably receives an Allen screw 24 which may be threaded inwardly to bear against the adjacent side surface of the vise jaw. The vise jaw will then be securely clamped between the inner surface of the ear 18 and the screw 24.

In order to prevent upward swinging of the face plate 10 about an axis corresponding to the screw 24, the hole 22 receiving the latter is disposed 45 substantially below the transverse medial line of the face portion 12 so that any tendency of the face plate to swing in that manner causes the part of the portion 12 above the axis of the screw 24 to bear against the gripping face of the vise jaw for resisting such swinging.

Upward swing of the face plate, which may result from gripping of the work only between the uppermost parts of the faces 14, is further avoided by forming the flange 20 so that it has 50 a thickness of not much more than one-sixteenth

of an inch with the top edge of the face 14 being flush with the upper surface of the flange. Thus, even when the work is gripped only between the uppermost parts of the faces 14, the reaction to the gripping force will act along a line that is not much above the top edge of the gripping face of the vise jaw against which the face portion 12 bears, and the moment available for swinging the face plate 10 will be correspondingly small.

In Fig. 5, two identical face plates 10 and 10' are shown mounted upon the jaws 26 and 28 of a conventional vise 30. It will be noted that the same face plates are adapted for use on either of the jaws merely by reversing their positions so that the faces 14 and 14' are confronting to grip a piece of work 32 therebetween, with the ear 16 of one, bearing the holding screw 24, being positioned at the same side of the vise as the ear 18 of the other.

From the foregoing, it is apparent that no 20 modification of the vise jaws is required in order to adapt them for mounting of the face plates thereon, and that the arrangement of the holding screw 24 permits the mounting of the described face plate on vise jaws of different sizes while 25 in each case resisting swinging or other displacement of the face plate relative to the vise jaw.

While I have described and illustrated a preferred embodiment of the present invention, it is to be noted that the latter is not limited to that precise embodiment, and that changes and modifications, obvious to one skilled in the art, may be made therein without departing from the scope or spirit of my invention.

What I claim is:

A face plate for mounting on a vise jaw comprising a face portion of substantially rectangular configuration formed to extend across and

cover the gripping face of an associated vise jaw, ears on the opposite end of said face portion and extending rearwardly therefrom to loosely receive the sides of the associated vise jaw therebetween, a flange extending rearwardly from said face portion flush with the top edge of the latter to rest upon the top of the associated vise jaw, said flange being integral at its opposite ends with said ears to resist spreading apart of the latter and having a relatively small thickness so that the part of said face portion extending above the associated vise jaw is correspondingly small, and an Allen screw threadedly extending through one of said ears to adjustably bear against the adjacent side of the associated vise jaw, said screw being disposed to rotate about an axis located substantially below the transverse medial line of said face portion to prevent upward swinging of the latter.
